Inventor
Parker K. Baird

Herbert S. Smith

Attorney

UNITED STATES PATENT OFFICE.

PARKER K. BAIRD, OF SPOKANE, WASHINGTON.

FOURDRINIER MACHINE.

Application filed May 2, 1921. Serial No. 466,111.

To all whom it may concern:

Be it known that I, PARKER K. BAIRD, a citizen of the United States, residing at Spokane, in Spokane County and State of Washington, have invented certain new and useful Improvements in Fourdrinier Machines, of which the following is a specification.

The present invention relates to improvements in Fourdrinier machines, for use in the process of making paper and the formation of the web thereof, the primary object of the invention being the provision of means for eliminating the foam or froth that is otherwise likely to develop on and in the stuff or paper stock as it flows onto the wire; and this means may be applied to other similar application for foam eliminations. In paper making machines probably due to the agitation of the stuff, a foam or froth is formed, consisting of air bubbles, which, if permitted to remain on and in the web being formed on the wire, results in causing thin and weak spots in the web as the web passes toward the couch roll. The presence in sufficient quantity of these bubbles, consequently weakens the web causing it to break, necessitating the carrying of the web through the paper machine again with resultant loss of labor, power and production.

To overcome this objectionable feature, I have found by experiment that the application of high tension unidirectional current to the field of the foam or froth causes a breaking down and elimination of these bubbles, either mechanically or by neutralizing the charges of the colloidal foam-causing materials by the electrostatic discharge and ionization of the field, and this desired result is accomplished with thoroughness and comparatively slight expense.

In the accompanying drawing I have illustrated one complete example of the physical embodiment of my invention, wherein the parts are combined and arranged according to the best mode I have thus far devised for the practical application of the principles of my invention.

Figure 1 illustrates in perspective, a portion of a Fourdrinier paper making machine, with the electrical device of my invention attached thereto.

Figure 2 is an electrical diagram illustrating the electric circuits.

In order that the application of my invention to the paper making machine may be clearly understood I have indicated pertinent portions of the machine, as the boxes 1 for the flow of stuff at the breast of the machine to the apron 2, which latter is made up of wire screen in the form of an endless belt on the supporting rollers at the ends thereof, as indicated at 3. The deckle belts 4, 4 as usual pass over the guide wheels 5, which are supported on the side bars 6 of the frame which includes supporting pedestals 7.

The endless wire screen moves in the direction of the arrow in the figure of drawing, and as the stuff for the web is taken up on the moving wire after the latter passes from under the roller 3 a foam or froth is likely to occur, forming a coating or layer of bubbles, and the presence of this foam, as before pointed out results in an inferior product, as well as causing waste of energy and production.

To destroy and eliminate the foam or bubbles I suspend across the machine, transversely thereof, and above the upper flight of the apron a series of spaced electric antennæ 8, in the form of wire, connected to end bars 9, extending longitudinally of the machine. The bars 9 are supported from pairs of posts 10 attached to the side bars 6 of the machine, and adjustable connections 11 between the posts and side bars 9 complete the means for suspending the antennæ or wires in horizontal position across the machine and at a proper height above the web forming apron 2. One feed wire 12 is connected to one of the side bars 9 and the other feed wire 13 is grounded on the side bar 6 of the machine to complete the electric circuit through the apron. A step-up transformer 14 and rectifying device 15 (Fig. 2) are interposed in the circuits to produce the high tension unidirectional current to the requirements of the electrical device including the antennæ 8, and of course the usual boards, switches, and other accessories are utilized in connection with the application of electrical energy.

When the current of electricity is furnished to the several antennæ 8, the field thereabout is electrically charged, and as the conductors are imposed directly over the apron and the web being formed thereon, any bubbles or foam created in the stuff on

the apron will come under the influence of the electrostatic discharge resulting in the deformation of the bubbles or foam and thus preventing the formation of thin and 5 weak spots in the subsequently treated web with its deleterious effects.

10 The antennæ 8 may be adjusted as desired to provide an electrically charged field directly over the apron 2, to insure adequate influence of the charge for eliminating the bubbles or foam, and when this field is so charged the eliminating of foam is accomplished.

15 While the invention above described is applicable to use on the Fourdrinier end of a paper making machine the same means and devices may be employed in connection with other industries such as the sugar-making industry, or in connection with 20 evaporators of liquors wherein by agitation or other causes a foam, froth or bubble formation is caused. In connection with sugar carbonators and the evaporating of liquors the application of high tension unidirectional 25 current will cause a break down of the foam or the like which will overcome the necessity of shutting down the plant during the period in which this foam or froth appears.

30 Having fully described my invention,

what I claim as new and desire to secure by Letters Patent is:—

1. In a Fourdrinier machine, the combination with the apron thereof and machine frame, of means for electrostatically 35 charging the atmosphere directly over said apron, for the purpose described.

2. In a Fourdrinier machine, the combination with the apron thereof and the machine frame, of means for applying thereto 40 high tension unidirectional electricity for the purpose described.

3. In a Fourdrinier machine, the combination with the apron thereof and machine frame, of transversely arranged electrical 45 antennæ imposed over said apron for the purpose described.

4. In a Fourdrinier machine, the combination with the apron thereof and machine frame, of posts on said frame, a series of 50 spaced, transversely imposed electrical antennæ imposed directly over said apron, side bars for supporting said antennæ, supporting devices between said bars and posts, and electrical connections to said bars, for 55 the purpose described.

In testimony whereof I affix my signature.

PARKER K. BAIRD.
